UNITED STATES PATENT OFFICE.

WILLIAM ARTHUR RAMSAY, OF HONOLULU, TERRITORY OF HAWAII.

APPARATUS FOR MACERATING SUGAR-CANE.

1,191,826.

Specification of Letters Patent. Patented July 18, 1916.

Application filed April 6, 1914. Serial No. 830,000

To all whom it may concern:

Be it known that I, WILLIAM ARTHUR RAMSAY, a subject of the King of Great Britain, residing at Honolulu, in the Territory of Hawaii, have invented certain new and useful Improvements in Apparatus for Macerating Sugar-Cane, of which the following is a specification.

This invention relates to improvements in apparatus for macerating sugar cane, proposing an apparatus which may be arranged at the outlet side of a mill of ordinary construction.

The principal objects of the invention, briefly stated, are to provide for a more thorough maceration of the cane and with a smaller amount of dilution liquid than is possible with the methods and machines ordinarily employed; to improve the feed of the bagasse as it passes from one crushing or extracting mill to the mill next in order in the series; and to provide a construction for the purpose stated which shall be readily applicable to existing mills and requires no departure from accepted standards of mill construction. The great advantage which results from these objects is that of economy, since a material saving is effected in the operation of evaporating the sugar bearing liquid extracted by the mills, the number of mills required is reduced, the crushed cane or bagasse is uniformly treated throughout the series and is thoroughly acted on by each mill, and the feeding of the bagasse through the series of mills is materially simplified and improved.

It is customary to spray the cane or bagasse as it leaves the mill with water, which takes up a percentage of the sugar and is subsequently treated by evaporation for the purpose of concentrating the sugar. It is important to use as little water as possible for the purposes in view, owing to the expense involved in the evaporation process. The bagasse, as it leaves the mill, is exposed to the atmosphere and the water used to take up the sugar is simply sprayed upon the passing stream of material. When the bagasse passes from the mill it expands, since, being exposed to atmosphere and relieved from mechanical pressure, its cells become filled or substantially filled with air. Inasmuch as the water cannot thoroughly permeate the air-filled cells of the bagasse, the action of the water is largely superficial,

and it follows that the amount of sugar which is actually taken up by the water represents a relatively small percentage of the amount of sugar which the same quantity of water could absorb, were it possible for it to thoroughly permeate the cellular structure of the bagasse. In practising this, the ordinary method of maceration, repeated and proportionately excessive spraying of the bagasse is required.

One important feature of the present invention consists in continuing the exercise of mechanical pressure upon the traveling stream of bagasse as it leaves the mill for the purpose of excluding, or substantially excluding, air, and in simultaneously forcing water under pressure into the mechanically compressed traveling stream in such manner that the water thoroughly permeates the cellular structure of the bagasse. In this way the amount of sugar absorbed is greatly increased. In fact, a substantially smaller amount of water than is ordinarily employed will absorb a substantially greater amount of sugar. This feature of the invention may be effectively carried out in a construction wherein water is admitted to only one side of the traveling stream of bagasse. The best results, however, are obtained by admitting water at opposite sides of the traveling mass, *i. e.*, above and below the same, and it is therefore preferred to use a construction which will project two oppositely directed streams of water into the relatively thin sheet of traveling, mechanically compressed, bagasse.

In practising the ordinary method of maceration, several crushing or extracting mills are arranged in series or in tandem, and special mechanism is provided to transfer the bagasse from one mill to the mill next in order in the series. It is usual to allow the bagasse, as it passes from the discharge end of a mill, to drop from the discharge roller upon an apron conveyer composed of steel slats or canvas belting, which said conveyer elevates the bagasse and discharges it into the mouth of the succeeding mill.

A second important feature of the present invention is directed to the transfer of the bagasse from the mill to a succeeding mill, and involves the elimination of the usual mechanical transferring agencies and the utilization of the whole or a part of the ejecting power of the top and discharge

roller of the mill to effect the transfer of the mash to the next mill.

The mechanical agency employed to effect the maceration of the bagasse, and which, for the sake of convenience, may be broadly termed a macerating scraper, includes essentially, a shoe arranged immediately adjacent the discharge end of the mill and constructed to uninterruptedly continue the mechanical compression of the bagasse as it passes from the mill and also to deliver into the passing stream of bagasse a volume of water which, the air being substantially excluded from the cells of the bagasse, thoroughly permeates the same.

In the preferred embodiment of the invention, the macerating scraper consists of a pair of co-operative shoes, each constructed as just described and between which the bagasse passes as it issues from the mill.

The mechanical agency employed to effect the transfer of the bagasse consists of a chute or conduit which in the embodiment of the invention herein disclosed is open only at its ends and is used essentially in combination with a macerating scraper of the construction outlined. An important feature of said chute is that for an initial portion of its length it is inclined upwardly to conform to the upward angle of inclination at which the bagasse is discharged from the ordinary three-roll mill and for the remainder of its length is inclined downwardly to facilitate the passage of the bagasse to the next succeeding mill. The chute as an entirety is of curved form in order that the transmission from the upward to the downward direction of travel may be gradual and that the friction due to the annular direction of travel of the bagasse may be minimized and the load, against which the ejecting power of the mill works, may be relatively small. The bagasse, as it passes from the scraper, enters the chute or conduit and is propelled therethrough by the ejecting power of the top and discharge rollers of the mill. The chute maintains mechanical pressure upon the bagasse and in the embodiment disclosed substantially excludes air therefrom. In this way the bagasse is prevented from having any substantial expansion and consequently, is more readily and uniformly taken up by the mill to which it is fed. Moreover, the continuation of the mechanical pressure upon the stream of bagasse, after the water has been projected thereinto, and throughout the period in which the bagasse is traveling to the succeeding mill, insures of the thorough sugar absorbing action of the water and materially promotes the purpose for which the water is employed. The water incorporated in the bagasse acts as a lubricant upon the walls of the chute or conduit, and this insures that the ejecting power of

the top and discharge rollers of the mill shall be amply sufficient to propel the bagasse through said chute or conduit, without any liability of the choking of the discharge mouth of the chute.

The macerating scraper to which reference has been made may be employed by itself or in combination with the chute or conduit described, the latter arrangement being preferred.

The invention includes as an ancillary feature the provision of means for automatically adjusting the portion of the shoe or the upper shoe of the scraper in order that said shoe may be held in constant relation to the "floating" top roll of the mill, regardless of the rising and falling action of said roll due to variations in the thickness of the stream of bagasse.

The chute or conduit referred to and employed to effect the transfer of the bagasse to the succeeding mill preferably includes a wall which may be adjusted to vary the dimensions of the internal space of said chute or conduit to accord with the normal stream capacity of the mill or to meet other conditions of use.

The invention also includes various minor and collateral features of construction, combination, and arrangement of parts, which will be clearly pointed out as the description proceeds.

Apparatuses embodying the invention are illustrated in the accompanying drawings, wherein:—

Figure 1 is a longitudinal sectional view of a preferred construction wherein the scraper and the chute or conduit are employed in combination; Fig. 2 is a plan view of the same; Fig. 3 is a detail fragmentary cross sectional view of the chute or conduit; Fig. 4 is an enlarged longitudinal sectional view showing the construction of the macerating scraper employed in the apparatus of Fig. 1; Fig. 5 is a detail perspective view of the macerating scraper and its appurtenances; Fig. 6 is a detail perspective view of a bracket which is used as a means of support for the scraper; Fig. 7 is a detail fragmentary horizontal sectional view; Fig. 8 illustrates a modified construction wherein the scraper embodies but a single shoe and the chute or conduit is not employed; Fig. 9 is an enlarged longitudinal sectional view of the modified scraper *per se*; Fig. 10 is a rear elevation of the modified scraper and its appurtenances; and Fig. 11 is a horizontal sectional view on the line 11—11 of Fig. 9.

Similar characters of reference designate corresponding parts throughout the several views.

Fig. 1 shows diagrammatically two sugar mills A and B, arranged in tandem. This number is selected merely for the purposes

of illustration, since the plane may include, in a tandem arrangement, any desired number of such mills. The mills A and B may be of any desired construction, and, *per se*, 5 form no part of the invention. The drawings assume, however, a mill of customary construction, in which three rolls are employed, *e. g.*, two lower rolls and a top roll arranged symmetrically of the lower rolls; 10 and certain of the structural features of the apparatus forming the invention, in so far as their mere design is concerned, are specially constructed with a view to coöperation with the usual three roll mill.

15 For the purpose of illustration, the drawings show the discharge side of the mill A and the feed side of the mill B.

The incinerating scraper is arranged in relation to the mill A and, as shown in Fig. 1, comprises a pair of shoes 2 and 3, which are similar in construction, the shoe 2 being arranged adjacent the top roll *a* and the shoe 3 being similarly arranged adjacent the lower discharge roll *b*.

20 The shoes 2 and 3 are arranged transversely of the mill and are substantially co-extensive with the working faces of the rolls which they closely adjoin and parallel. In the preferred construction shown, each shoe 25 includes a casting 4 having a toe piece 5 projecting toward the adjoining mill roll, and a chamber 6 located beyond said toe piece. The toe piece 5 has its outer face beveled near its outer edge to conform to 30 the curvature of the roll which it adjoins, and also provided with grooves 7, as shown in Fig. 5, to match with the usual peripheral grooves of said roll. The toe pieces 5 have flat or regular inner faces which define a 35 discharge way 8 for the stream of bagasse ejected by the mill. Beyond the toe pieces 5 this discharge may be continued by the provision of flat plates 9 which adjoin the chambers 6 and are secured by bolt and nut 40 fastenings 10 against the inner faces of the castings 4. The bolt heads which engage the plates 9 are countersunk, so as to present no obstruction to the flowing stream of bagasse. The plates 9 form the inner walls of the 45 chambers 6, which are provided to effect the uniform distribution and delivery of a volume of water into the bagasse. The castings 4 are formed with internal shoulders 50 55 at the junction of the toe pieces and the chambers 6, and the plates 9 terminate short of said shoulders, thus providing passages 12 through which water discharges from the chambers 6 into the space between said plates. The shoulders 11 have their faces so 60 curved or inclined as to direct the water rearwardly into the stream of bagasse. (*i. e.* in the direction of travel of said stream), such direction of the projected stream of water being favorable to the propulsion of 65 the bagasse by the ejecting power of the rolls

a and *b*, and also being favorable to the thorough permeation of the bagasse by the water. Each casting 4 is provided with a suitable water inlet connection or connections 13. Preferably two water inlet connections are employed, as shown. For the purpose of reinforcement, the castings are provided with a row of lugs 14, suitably spaced from one another, which lugs extend to the plates 9 and are located slightly in advance of the passages 12. The lugs 14 provide a plurality of ducts through which the inner portions of the chamber 6 communicate with the passages 12 and the latter are of relatively narrow dimensions so as to deliver the water with considerable force and in a thin but wide sheet into the bagasse. The water entering the chambers 6 is thus subdivided by the lugs 14 into a plurality of streams and is, therefore, uniformly distributed throughout the extent of the passages 12 and hence uniformly distributed throughout the width of the passing stream of bagasse.

70 The stream of bagasse which discharges 90 from the mill is subject to mechanical compression in the chamber 8 and for this purpose said chamber must be closed at its ends. The top roll of the sugar mills is usually 95 provided with end flanges *a'*. The scrapers, as above stated, are co-extensive with the working faces of the rolls and their toe pieces 5 project between the flanges *a'* whereby said flanges constitute end closures for a portion of the passage 8. To completely 100 close the ends of said passage, side plates 15 are employed and said side plates are formed with curved edges 16 which conformably fit against the flanges *a'*, and adjacent the passage 8 are beveled off as at 17 so as to present no obstruction to the stream of bagasse ejected by the mill. The side plates 15 are formed to project beyond and to overlie the ends of the lower discharge roll *b*. Any suitable means may be employed for supporting the scrapers.

105 In the preferred form of the invention, and in consideration of the movement of the scrapers relatively to one another in accordance with the floating or rising and falling action of the top roll, the support for the scrapers comprises transverse bars 18 secured to the outer faces of the plates 9 beyond the castings 4 and having their ends, which project beyond said plates, fitted in 110 angle brackets 19, which latter are suitably connected to the mill housings or head stocks 115 of the machine. The bars 18 have a square cross section and at their ends are formed with trunnions 20 which engage in bearing 120 openings 21 in the side members of the angle brackets 19. The bars 18 are thus pivotally movable about their longitudinal axes, for the purpose of providing for adjustments of the spacing of the scrapers rela- 125 130

tively to one another. To effect such adjustments, arms 22 are mounted on the end portions of said bars, and project rearwardly therefrom, said arms terminating at their 5 rear ends in alining eyes 23. A bolt 24 passes loosely through the eyes 23 and has at one end a nut 25. The arms 22 have square openings generally conforming to the cross-section of the bars 18 and through 10 which said bars project. In this way the arms are fixed against pivotal movement relatively to the bars, and it follows that the nut 25 may be actuated to draw the arms together or to permit them to move apart, in 15 which case, the bars 18 will be rotated to a very slight extent and being rigidly connected to the plates 9, which plates are rigidly connected to the castings 4, will effect corresponding adjustments of the shoes relatively to one another, and hence, will vary 20 the vertical dimension of the passage 8. The inherent resiliency of the arms 22 may be relied on to insure of the contact of the upper shoe with the floating top roll which 25 rises and falls, as usual, according to variations in the thickness of the stream of bagasse. Expansive coil springs may, however, be arranged under the nuts 25 for this purpose, if their use in particular cases 30 should prove desirable.

It will be observed that the passage 8 is defined partly by the toe pieces 5 and partly by the plates 9, which latter have a greater spacing than said toe pieces, and that the 35 passages 12 open into the passage 8 between the toe pieces and said plates 9. It follows, therefore, that the mechanical pressure to which the stream of bagasse is subjected is greater in that portion of the passage 8 which is defined by the toe pieces 5 than it is 40 in the rest of said passage, and that the water which is forced into the bagasse is admitted to the same when the latter is in an expanding state due to the reduction of 45 mechanical pressure which takes place when the bagasse passes between the plates 9. This fact, coupled with the fact that air is substantially excluded from the passage 8 and that the water is discharged into said passage by 50 the passages 12 with considerable force and in a thin but wide sheet, assures that the bagasse will be thoroughly permeated by the water.

As previously stated, the macerating 55 scraper is preferably combined with a chute or conduit, which extends to the succeeding mill. This chute or conduit continues the mechanical compression of the bagasse and the exclusion or substantial exclusion of air 60 therefrom, and thus favors the thorough action of the water, and it also enables the ejecting power of a mill to be utilized for effecting the transfer of the bagasse to the succeeding mill. The chute or conduit may 65 have any construction suitable for the pur-

poses in view, but it is preferably of the construction shown in the drawings.

Fig. 1 shows a chute or conduit which is designated generally by the numeral 26 and which extends between the macerating 70 scraper of the mill A and the succeeding mill B and forms, in effect, a continuation of the passage 8. The chute or conduit 26 comprises a bottom wall 27, a top wall 28, and side walls 29 and is so associated with 75 the scraper that there is no interruption between its internal space and the passage 8. As shown and preferred, the plates 17 project into the adjacent end of the chute 26, in overlapping relation to the top and bottom walls thereof, and said plates are rigidly secured to said walls by means 29 or other suitable means. The plates 17 which form the end walls of the passage 8 are horizontal and the side walls 29 of the chute 26 and are provided with forward extensions 30 which abut the adjacent ends of said side walls and form therefrom a 35 combination, as at 31, for closing the outer faces of the walls 29 and it is to be understood that the inner faces of said walls shall be closed, while the inner faces of the plates 17.

In the construction shown, provision is made for adjusting the vertical dimension of the chute 26. For this purpose the top wall 28 is 40 adjustably movable between the side walls 29 and the latter project throughout their length, for some distance beyond said top wall. The support for the adjustable top wall includes at the front end of said 45 wall, the positive connections between said wall and the plate 8 of the adjacent intervening shoe and, at the rear end of said wall, links 32 which are pivoted to the reinforcing angle iron strips 33 provided at the longitudinal marginal edges of the wall 28. Each link 32 is provided with a row of openings 34 through one end of which a pin or screw 35 which engages in the adjacent wall 29 may be inserted. In making an adjustment, the pins 35 are disengaged and the wall is sprung or permitted to spring into the desired position, after which the links 32 are again connected by the pins or bolts 35 to the walls 29.

The chute or conduit 26 as well as the passage 8 by preference gradually increases in volume toward its discharge end in order that the bagasse may gradually expand as it approaches the mill B. Such gradual expansion of the bagasse coupled with the time element involved in the travel of the bagasse through said chute materially promotes the access of the water to the cells of the bagasse and hence aids the sugar absorbing action of the water.

When the usual stone mill is employed the bagasse is removed from the mill at an upward angle of inclination and is delivered into the macerating mill at a down- 130

ward angle of inclination. The passage 8 is, therefore, directed rearwardly and upwardly, and the chute 26 is of curved form in order that the transmission from the upward to the downward direction of travel 5 may be gradual. By so forming the chute, the ejecting power of the mill A is amply sufficient for the purposes in view since friction due to the angular direction of travel of 10 the bagasse is minimized and the load against which said ejecting power works (being a fractional part of the weight of that portion of the bagasse which is in the passage 8 and the upwardly directed forward end of the chute) is relatively small. The water which is delivered to the bagasse acts as a lubricant in the chute and thus facilitates the passage of the bagasse through the chute. The bagasse is readily 15 taken up by the mill B since it has a uniform consistency, is fed to said mill in uniform volume and at a uniform rate of speed, and is fed in such direction that a percentage of the weight of the stream (being a fractional 20 part of the weight of that portion of the bagasse which is in the downwardly directed rear portion of the chute) influences the passage of the bagasse between the top roll and the lower feed roll.

30 The walls of the chute 26 can advantageously be made of sheet metal of requisite gauge, suitably reinforced to withstand the internal pressure by angle iron bars or equivalent means.

35 The angle brackets 19 which support the shoes of the macerating scraper also support the front end of the chute, as is obvious. For the support of the rear end of the chute angle brackets 37, connected to the housing 40 or head stocks of the mill B and to the walls 29 of the chute, may be employed.

45 The walls 29 of the chute are formed at their rear ends with curved edges 38 which conform to the curvature of the end flanges α' of the top roll of the mill B and closely fit said flanges. Said walls are also formed at their rear ends to overlie the ends of the feed roll of said mill.

50 Figs. 8 to 10 show a modified construction wherein the macerating scraper comprises but one shoe and the chute or conduit 26 is not employed. In this case the scraper includes a toe piece 5^a, a chamber 6^a and a compression plate 9^a arranged under said chamber. The under faces of the toe piece and compression plate conform generally to the curvature of the lower discharge roll b but are preferably so directed that the compression passage 5^a between said under faces and 55 the discharge roll flares toward its discharge end. Moreover, the curved under face of the compression plate 9^a is offset from the under face of the toe piece to provide for an abrupt enlargement of the compression space 60 and a consequent abrupt but slight reduction

65 of pressure on the bagasse. The chamber 6^a communicates with the passage 8^a by means of a relatively narrow passage 12^a which directs the water rearwardly, *i.e.*, in the direction of travel of the bagasse and coincides 70 with the point of abrupt enlargement of the passage 8^a as above explained.

75 The scraper is supported by means of arms 38 which are keyed on a transverse shaft 39 journaled in bearings carried by the mill housing. The shaft 39 is provided with arms 40 which extend at an angle to the arms 38 and have their outer ends connected to adjusting links 41, in turn connected to the mill housing. The links 41 include turn-buckles 42 which may be operated in the well-known manner to lengthen or shorten said links and to correspondingly rotate the shaft 39 and move the scraper upwardly or downwardly as the case may be, accordingly as 80 the mechanical pressure on the bagasse is to be decreased or increased.

85 The chamber 6^a is preferably made in two divisions separated by a central partition 6^b, each division having its water inlet connection 13^a. In this modified construction provision may be made for regulating the effective capacity of the passage 12^a. For this purpose valves 43 are arranged in each division of the chamber 6^a, said valves being slidably mounted upon the bottom of said chamber and being operated by stems 44 which are threaded through the rear wall of the chamber 6^a and are provided with lock nuts 45.

90 The toe piece, compression plate, and top wall sections 6^c of the chamber 6^a are preferably made as separate parts and are secured to the adjoining walls of the chamber 6^a by fastening screws or other means. The top wall sections 6^c may, as shown, be formed 95 integral with the arms 38.

100 For transferring the bagasse to the succeeding mill the usual belt conveyer C may be employed, as shown, in which case the bagasse will be deposited upon said belt by the lower discharge roll b of the mill. The side frame members of the conveyer C may be provided with extensions 46 which fit 105 against the flanges α' of the top roll a and close the ends of the passage 8^a to exclude 110 air from said passage or other means suitable for this purpose may be employed.

115 The chute or conduit 26 is herein disclosed in combination with a scraper which comprises a pair of macerating shoes. It will be 120 understood, however, that said chute or conduit may be employed in combination with a scraper which comprises but one macerating shoe, the changes involved in effecting this combination being merely colorable variations in design.

125 It will also be understood that the particular constructions herein disclosed, while preferred, are to be regarded merely as examples, and, therefore, that no specific description 130

tion herein contained is intended to impose any limitation upon the scope of the appended claims not inherent in the language thereof.

5 Having fully described my invention, I claim:

1. The combination with a sugar mill of a macerating scraper including a shoe arranged adjacent the discharge side of the mill to define a passage through which the bagasse travels and to subject the bagasse issuing from the mill to mechanical pressure, and means for delivering water into the bagasse as it travels through said passage.
- 13 2. The combination with a sugar mill of a macerating scraper including a shoe arranged adjacent the discharge side of the mill to define a passage through which the bagasse travels and to subject the bagasse issuing from the mill to mechanical pressure, means for delivering water into the bagasse as it travels through said passage, and means adjacent the ends of said shoe for closing the ends of said passage.
- 20 3. The combination with a sugar mill of a macerating scraper including a shoe arranged adjacent the discharge side of the mill and having a toe piece which projects into the discharge way of the mill and a water distribution chamber in the rear of the toe piece provided with a water inlet connection and a water discharge passage, the shoe defining a passage through which the bagasse travels and subjecting the bagasse as it is discharged by the mill to mechanical pressure, the water discharge passage communicating with the passage through which the bagasse travels.
- 25 4. The combination with a sugar mill of a macerating scraper including a shoe arranged adjacent the discharge side of the mill and having a toe piece which projects into the discharge way of the mill and a water distribution chamber in the rear of the toe piece provided with a water inlet connection and a water discharge passage, the shoe defining a passage through which the bagasse travels and subjecting the bagasse as it is discharged by the mill to mechanical pressure, the water discharge passage communicating with the passage through which the bagasse travels.
- 30 5. The combination with a sugar mill of a macerating scraper including a shoe arranged adjacent the discharge side of the mill and having a toe piece which projects into the discharge way of the mill and a water distribution chamber in the rear of the toe piece provided with a water inlet connection and a water discharge passage, the shoe defining a passage through which the bagasse travels and subjecting the bagasse as it is discharged by the mill to mechanical pressure, the water discharge passage communicating with the passage through which the bagasse travels.
- 35 6. The combination with a sugar mill of a macerating scraper including a shoe arranged adjacent the discharge side of the mill and having a toe piece which projects into the discharge way of the mill and a water distribution chamber in the rear of the toe piece provided with a water inlet connection and a water discharge passage, the shoe defining a passage through which the bagasse travels and subjecting the bagasse as it is discharged by the mill to mechanical pressure, that portion of the bagasse passage which is defined by the toe piece being narrower than the rest of said passage, the water discharge passage communicating with the passage through which the bagasse travels at a point immediately in the rear of the toe piece.
- 40 7. The combination with a sugar mill of a macerating scraper including a shoe arranged adjacent the discharge side of the mill to define a passage through which the bagasse travels and to subject the bagasse issuing from the mill to mechanical pressure, means for delivering water into the bagasse as it travels through said passage, and means for adjusting the position of the shoe.
- 45 8. The combination with a sugar mill of a macerating scraper including a shoe arranged adjacent the discharge side of the mill and comprising a casting which is formed with a toe piece to project into the discharge way of the mill and with a water distribution chamber in the rear of the toe piece, provided with a water inlet connection, and a plate secured to said casting in the rear of the toe piece and forming the base of said chamber, the casting having an internal shoulder between the chamber and the toe piece and the plate being spaced from said shoulder to provide a passage immediately in the rear of the toe piece through which water discharges from the chamber, the shoe defining a passage through which the bagasse travels and subjecting the bagasse as it is discharged by the mill to mechanical pressure, the water discharge passage communicating with the passage through which the bagasse travels.
- 50 9. The combination with a sugar mill of a macerating scraper including a shoe arranged adjacent the discharge side of the mill and comprising a casting which is

- formed with a toe piece to project into the discharge way of the mill and with a water distribution chamber in the rear of the toe piece, provided with a water inlet connection, a plate secured to said casting in the rear of the toe piece and forming the base of said chamber, the casting having an internal shoulder between the chamber and the toe piece and the plate being spaced from said shoulder to provide a passage immediately in the rear of the toe piece through which water discharges from the chamber, the shoe defining a passage through which the bagasse travels and subjecting the bagasse as it is discharged by the mill to mechanical pressure, the water discharge passage communicating with the passage through which the bagasse travels, and a row of lugs arranged in the chamber and extending to the plate, the lugs reinforcing the casting and defining a plurality of ducts through which the chamber communicates with the water discharge passage.
10. The combination with a sugar mill of a macerating scraper including a shoe arranged adjacent the discharge side of the mill and comprising a casting which is formed with a toe piece to project into the discharge way of the mill and with a water distribution chamber in the rear of the toe piece, provided with a water inlet connection, a plate secured to said casting in the rear of the toe piece and forming the base of said chamber, the casting having an internal shoulder between the chamber and the toe piece and the plate being spaced from said shoulder to provide a passage immediately in the rear of the toe piece through which water discharges from the chamber, the shoe defining a passage through which the bagasse travels and subjecting the bagasse as it is discharged by the mill to mechanical pressure, the water discharge passage communicating with the passage through which the bagasse travels, the plate projecting rearwardly beyond the casting, and a rotatably mounted bar which supports the shoe and to which the rearwardly projecting portion of the plate is secured.
15. The combination with a sugar mill of a macerating scraper including a pair of shoes arranged to project into the discharge way of the mill to define a passage through which the bagasse travels and to mechanically compress the bagasse, one of the shoes having a water distributing chamber and a water discharge passage leading from said chamber into the passage for the bagasse.
20. The combination with a sugar mill of a macerating scraper including a pair of shoes arranged to project into the discharge way of the mill to define a passage through which the bagasse travels and to mechanically compress the bagasse, each of the shoes having a toe piece, a water distributing chamber in the rear of the toe piece and a water discharge passage leading from the chamber at a point immediately in the rear of the toe piece into the passage for the bagasse, the said bagasse passage having less width between the toe pieces and greater width between the bases of the water distributing chambers.
25. The combination with a sugar mill of a macerating scraper including a pair of shoes arranged to project into the discharge way of the mill to define a passage through which the bagasse travels and to mechanically compress the bagasse, each of the shoes having a water distributing chamber and a water discharge passage leading from said chamber into the passage for the bagasse and an adjustable means of support for one of the shoes whereby the position thereof relative to the other shoe may be varied.
30. The combination with a sugar mill of a macerating scraper including a pair of shoes arranged to project into the discharge way of the mill to define a passage through which the bagasse travels and to mechanically compress the bagasse, each of the shoes having a water distributing chamber and a water discharge passage leading from said chamber into the passage for the bagasse and parallel rotatably mounted bars by which the shoes are respectively supported.
35. The combination with successive sugar mills of a macerating scraper including a shoe arranged adjacent the discharge side of the first mill, the shoe defining a passage through which the bagasse travels and subjecting the bagasse to mechanical pressure as it is discharged by the mill, and means for delivering water into the bagasse passage; and a closed chute which forms a continuation of the bagasse passage and discharges the bagasse into the receiving side of the second mill.
40. The combination with successive sugar mills of a macerating scraper including a pair of shoes arranged adjacent the discharge side of the first mill to define a passage through which the bagasse travels and to subject the bagasse to mechanical pressure as it is discharged by the mill, and means for delivering water into the bagasse passage; and a closed chute which forms a continuation of the bagasse passage and dis-

having a water distributing chamber and a water discharging passage leading from said chamber into the passage for the bagasse whereby water is forced into the bagasse at opposite sides thereof.

76

13. The combination with a sugar mill of a macerating scraper including a pair of shoes arranged to project into the discharge way of the mill to define a passage through which the bagasse travels and to mechanically compress the bagasse, each of the shoes having a toe piece, a water distributing chamber in the rear of the toe piece and a water discharge passage leading from the chamber at a point immediately in the rear of the toe piece into the passage for the bagasse, the said bagasse passage having less width between the toe pieces and greater width between the bases of the water distributing chambers.

85

14. The combination with a sugar mill of a macerating scraper including a pair of shoes arranged to project into the discharge way of the mill to define a passage through which the bagasse travels and to mechanically compress the bagasse, each of the shoes having a water distributing chamber and a water discharge passage leading from said chamber into the passage for the bagasse and an adjustable means of support for one of the shoes whereby the position thereof relative to the other shoe may be varied.

90

15. The combination with a sugar mill of a macerating scraper including a pair of shoes arranged to project into the discharge way of the mill to define a passage through which the bagasse travels and to mechanically compress the bagasse, each of the shoes having a water distributing chamber and a water discharge passage leading from said chamber into the passage for the bagasse and parallel rotatably mounted bars by which the shoes are respectively supported.

100

16. The combination with successive sugar mills of a macerating scraper including a shoe arranged adjacent the discharge side of the first mill, the shoe defining a passage through which the bagasse travels and subjecting the bagasse to mechanical pressure as it is discharged by the mill, and means for delivering water into the bagasse passage; and a closed chute which forms a continuation of the bagasse passage and discharges the bagasse into the receiving side of the second mill.

110

17. The combination with successive sugar mills of a macerating scraper including a pair of shoes arranged adjacent the discharge side of the first mill to define a passage through which the bagasse travels and to subject the bagasse to mechanical pressure as it is discharged by the mill, and means for delivering water into the bagasse passage; and a closed chute which forms a continuation of the bagasse passage and dis-

115

charges the bagasse into the receiving side of the second mill.

18. The combination with successive sugar mills of a macerating scraper including a pair of shoes arranged adjacent the discharge side of the first mill to define a passage through which the bagasse travels and to subject the bagasse to mechanical pressure as it is discharged by the mill, and means for delivering water into the bagasse passage; and a closed chute which forms a continuation of the bagasse passage and discharges the bagasse into the receiving side of the second mill, the bagasse passage being upwardly directed and the chute being of curved form and being upwardly directed for an initial portion of its length and downwardly directed for the rest of its length. 80

19. The combination with successive sugar mills of a macerating scraper including a shoe arranged adjacent the discharge side of the first mill, the shoe defining a passage through which the bagasse travels and subjecting the bagasse to mechanical pressure as it is discharged by the mill, and means for delivering water into the bagasse passage; and a chute which forms a continuation of the bagasse passage and discharges the bagasse into the receiving side of the second mill. 85

20. The combination with successive sugar mills of a macerating scraper including a pair of shoes arranged adjacent the discharge side of the first mill to define a passage through which the bagasse travels and to subject the bagasse to mechanical pressure as it is discharged by the mill, and means for delivering water into the bagasse passage; and a chute which forms a continuation of the bagasse passage and discharges the bagasse into the receiving side of the second mill, the bagasse passage being upwardly directed and the chute being of curved form and being upwardly directed for an initial portion of its length and downwardly directed for the rest of its length. 95

21. The combination with successive sugar mills of a macerating scraper including a shoe arranged adjacent the discharge side of the first mill, the shoe defining a passage through which the bagasse travels and subjecting the bagasse to mechanical pressure as it is discharged by the mill, and means for delivering water into the bagasse passage; and a closed chute which forms a continuation of the bagasse passage and discharges the bagasse into the receiving side of the second mill, the chute having extended side walls and having a top wall adjustable between said side walls to vary the vertical dimension of its internal space. 100

22. The combination with successive sugar mills of a macerating scraper including a pair of shoes arranged adjacent the discharge side of the first mill to define a pas- 110

sage through which the bagasse travels and to subject the bagasse to mechanical pressure as it is discharged by the mill and means for delivering water into the bagasse passage; rotatably mounted bars by which the 70 shoes are supported; and a closed chute which forms a continuation of the bagasse passage and discharges the bagasse into the receiving side of the second mill, the chute having extended side walls and having its 75 top wall adjustable between said side walls to vary the vertical dimensions of the chute; the shoes having plates which project into the chute and are connected to the respective top and bottom walls thereof. 80

23. The combination with successive sugar mills of a macerating scraper including a pair of shoes arranged adjacent the discharge side of the first mill to define a passage through which the bagasse travels and to subject the bagasse to mechanical pressure as it is discharged by the mill, and means for delivering water into the bagasse passage; a closed chute which forms a continuation of the bagasse passage and discharges the bagasse into the receiving side of the second mill, and side plates arranged at the ends of the bagasse passage to close the same and having extensions which adjoin and overlap the side walls of the chute. 90

24. The combination with a sugar mill of a macerating scraper including a pair of shoes arranged to project into the discharge way of the mill to define a passage through which the bagasse travels and to mechanically compress the bagasse, one of the shoes having a water distributing chamber and a water discharge passage leading from said chamber into the passage for the bagasse, and means for adjusting the position of the 105 shoes relatively to one another. 100

25. The combination with a sugar mill of a macerating scraper including a pair of shoes arranged to project into the discharge way of the mill to define a passage through 110 which the bagasse travels and to mechanically compress the bagasse; each of the shoes having a water distributing chamber and a water discharge passage leading from said chamber into the passage for the bagasse, 115 and means for adjusting the position of the shoes relatively to one another.

26. The combination with a sugar mill of a macerating scraper including a pair of shoes arranged to project into the discharge 120 way of the mill to define a passage through which the bagasse travels and to mechanically compress the bagasse, and means for delivering water into the bagasse while under compression by the shoes. 125

27. The combination with a sugar mill of a macerating scraper including a pair of shoes arranged to project into the discharge way of the mill to define a passage through 130 which the bagasse travels and to mechani-

cally compress the bagasse, and means for adjusting the position of the shoes relatively to one another.

28. The combination with a sugar mill of means for mechanically compressing the bagasse as it issues from the discharge side of the mill, and means for delivering water into the bagasse during the period of compression.

10 29. The combination with a sugar mill of means for mechanically compressing the bagasse as it issues from the discharge side of the mill, means coacting with said first-named means to exclude air from the bagasse during its compression, and means for delivering water into the bagasse during the period of compression.

30. The combination with a sugar mill of means for mechanically compressing the bagasse as it issues from the discharge side of the mill, means for delivering water into the bagasse during the period of compression, and means for varying the position of said first-named means in accordance with variations in the thickness of the stream of bagasse.

31. The combination with successive sugar mills of a macerating scraper including a shoe arranged adjacent the discharge side 30 of the first mill, the shoe defining a passage through which the bagasse travels and subjecting the bagasse to mechanical pressure as it is discharged by the mill, and a chute which forms a continuation of the bagasse 35 passage and discharges the bagasse into the receiving side of the second mill, the bagasse passage being upwardly directed and the chute being of curved form and being upwardly directed for an initial portion of its 40 length and downwardly directed for the rest of its length.

32. The combination with a sugar mill of a macerating scraper including a pair of

coöperating shoes arranged adjacent the discharge side of said mill, the shoes defining a 45 passage through which the bagasse travels and subjecting the bagasse to mechanical pressure as it is discharged by the mill, and means for delivering water upon the bagasse compressed by the scraper. 50

33. The combination with successive sugar mills of a macerating scraper including a pair of shoes arranged adjacent the discharge side of the first mill, the shoes defining a passage through which the bagasse 55 travels and subjecting the bagasse to mechanical pressure as it is discharged by the mill, means for delivering water upon the bagasse compressed by the scraper, and a chute which forms a continuation of the 60 bagasse passage and discharges the bagasse into the receiving side of the second mill.

34. The combination with successive sugar mills of a macerating scraper including a pair of shoes arranged adjacent the discharge side of the first mill, the shoes defining a passage through which the bagasse travels and subjecting the bagasse to mechanical pressure as it is discharged by the mill, means for delivering water upon the 70 bagasse compressed by the scraper, and a chute which form a continuation of the bagasse passage and discharges the bagasse into the receiving side of the second mill, the bagasse passage being upwardly directed 75 and the chute being of curved form and being upwardly directed for an initial portion of its length and downwardly directed for the rest of its length.

In testimony whereof I have hereunto set 80 my hand in presence of two subscribing witnesses.

WILLIAM ARTHUR RAMSAY.
